(57) **CLAIM**

The ornamental design for an eyeglass temple as shown and described.

DESCRIPTION

FIG. 1 is a front, left and top perspective view of an eyeglass temple, showing my new design.

FIG. 2 is a rear, right and bottom perspective view thereof.

FIG. 3 is a front elevation view thereof.

FIG. 4 is a rear elevation view thereof.

FIG. 5 is an enlarged left side elevation view thereof.

FIG. 6 is an enlarged right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 2.

The dashed broken lines depict portions of the eyeglass temple that form no part of the claimed design. The dot-dash broken lines in FIGS. 1,2,9 and 10 depict the boundaries of the enlarged views and form no part of the claimed design. The oblique shade lines in the drawings indicate a transparent surface.
